UNITED STATES PATENT OFFICE.

RASMUS MARTIN HVID, OF BATTLE CREEK, MICHIGAN, ASSIGNOR TO R. M. HVID COMPANY, OF BATTLE CREEK, MICHIGAN, A CORPORATION OF MICHIGAN.

MEANS FOR DELIVERING OIL TO OIL-BURNING ENGINES.

1,134,858

Specification of Letters Patent

Patented Apr. 6, 1915.

Application filed August 16, 1912, Serial No. 715,519. Renewed November 30, 1914. Serial No. 874,906.

To all whom it may concern:

Be it known that I, RASMUS MARTIN Hvid, a citizen of the United States, residing at Battle Creek, in the county of Calhoun and State of Michigan, have invented new and useful Improvements in Means for Delivering Oil to Oil-Burning Engines, of which the following is a specification:

10 This invention relates to improvements in a means for delivering fuel-oil to the combustion space of an oil burning engine, and it proposes an improved construction which, in respect of certain of its novel features, is especially adapted for carrying out the method described and claimed in my co-pending application Serial No. 675,028, according to which a supply of oil is periodically maintained in a reservoir subject to 15 the heat in the combustion space and is forcibly ejected into said combustion space by an explosion of the vaporized constituents within the reservoir, the explosion being established by a diverted superheated 20 portion of the main air charge.

The improved oil-supplying means comprehends a reservoir in which the fuel oil is intermittently maintained in relation to the combustion space of the engine cylinder, and 30 one of the principal features of the invention is the novel relation which exists between this reservoir and the valve which controls the admission of fuel oil and auxiliary air thereto and whereby the objects to 35 be presently stated are served.

One object of the invention is to provide an oil-supplying means of the character generally identified above, which is not liable to carbon deposits, which may be manufactured at a minimum expense and at a low 40 intrinsic cost, and which is so simple in its structural details that there will be very little, if any, liability to breakage or undue wear, and, consequently, the necessities for 45 renewals or repairs will be very infrequent and a practically continuous satisfactory operation through a relatively long period of use will be insured.

A further object of the invention is to 50 provide an oil-supplying means for carrying out the method stated, wherein the explosion by which the fuel oil is expelled or ejected from the reservoir referred to into the engine cylinder is positively timed, as distin-

guished from a construction wherein there is no provision for positively timing the said explosion, but, on the contrary, the timing depends solely upon the alternate increases and decreases of the temperature of the air charge immediately adjacent the reservoir. By virtue of its capacity to serve this last object, the invention is especially and peculiarly adapted for oil burning engines of relatively large horsepower. The invention is, however, equally well adapted 65 for oil burning engines of relatively small horsepower, but in this latter instance, a positive timing of the explosion consequent to which the oil is expelled into the cylinder of the engine may not be so particularly required.

An embodiment of the invention is illustrated in the accompanying drawings, wherein:

Figure 1 is a sectional view showing the upper portion of an engine cylinder equipped with a fuel supply device in which the features of the invention are incorporated; Fig. 2 is a plan view of the same, partly in section; Fig. 3 is a detail longitudinal sectional view in the plane 3—3 of Fig. 6, showing the fuel supply device *per se*, with the valve thereof closed against its seat and the oil reservoir or cup positioned for the compression stroke of the piston; Fig. 4 is a similar view in the same plane, but showing the valve distant from its seat and the oil reservoir or cup positioned for the suction stroke of the piston; Fig. 5 is a detail fragmentary sectional and elevational view, the section being on the line 5—5 of Fig. 7, showing the position of the fuel reservoir at the time when fuel is being delivered into the combustion space of the engine cylinder; Fig. 6 is a detail horizontal sectional view in the plane 6—6 of Figs. 3 and 4; Fig. 7 is a detail horizontal sectional view in the plane 7—7 of Fig. 5; Fig. 8 is a detail horizontal sectional view in the plane 8—8 of Fig. 3; Fig. 9 is a detail horizontal sectional view in the plane 9—9 of Fig. 5; and Fig. 10 is an enlarged detailed sectional view showing the lower portion of the fuel reservoir when the latter is in the position of Fig. 4.

Similar characters of reference designate corresponding parts throughout the several views.

The engine cylinder is indicated generally by the letter A and the piston by the letter B. The cylinder may be of any approved construction, and, as shown, is provided with the usual cooling jacket a. The inlet valve 5 is shown at C and the exhaust valve at D. The valves C and D are shown as fitted in the upper head of the cylinder, and may be operated in any usual manner, for instance, 10 being held in closed relation by coil springs E and being opened by levers F which, in turn, are operated by the push rods G, the reciprocation of which is effected by the two-to-one cam shaft, (not shown). In the embodiment shown, the upper head of the engine is formed at one side thereof with a bore 1, in which is fitted a plug 2. The plug 2 has an extended inner portion 3 which is cupped to provide valve seat 4 and also to 20 snugly surround a valve 5. The plug 2 is formed with a passage 6, opening to the atmosphere, and with a passage 7, by which oil is fed, the passage 7 forming, in effect, a continuation of an oil supply pipe 8, which 25 leads from any suitable source of supply, for instance, an elevated tank (not shown). The passage 6 opens to the valve seat 4 and is controlled by the valve 5, the stem 11 of which may conveniently pass through said 30 passage and projects beyond the upper end of the plug 2. The projecting portion of the valve stem 11 is surrounded by an expansive coil spring 12, which acts on the head 13 at the upper end of said stem and serves to hold 35 the valve 5 in closed position. The valve 5 not only controls the passage 6, but it also controls the passage 7, the latter communicating with the valve seat 4 by a duct 14 of small diameter. The valve 5 is moved to 40 open position by a depression of its valve stem 11, a tappet 15, provided on the lever F, which operates the inlet valve C, being employed for this purpose. The tappet 15 carries at its end a screw 16 by means of 45 which the relative timing of the operation of the valves C and 10 may be regulated within certain limits. The passage 7, at its junction with the duct 14, is controlled by a fuel inlet valve 17, the stem of which projects 50 beyond the upper end of the plug 2 and is to be operatively connected in any suitable manner to the governor K.

The governor K may be of any suitable construction. As shown, it comprises the 55 well known centrifugal fly balls which are rotated at a suitable rate of speed by the spindle 19, geared in any desired manner to either the cam shaft or the crank shaft of the engine. When the speed of the engine 60 increases, the balls 20 swing outwardly, thereby, through the levers 21 and 22, lifting the governor weight 27, which surrounds the spindle 19 and has its lower end associated in any suitable manner with the forked end of a lever 23. The lever 23 is pivoted

on a bracket 24, which may be suitably located on the upper head of the engine, and it is suitably pivoted to the projecting upper end of the fuel inlet valve 17. It will be noted that when the engine is still, or when its speed is not high enough to bring the governor into action, the lower end of the governor will rest against the stop collar 25 on the spindle 19, and the valve 17 will have its highest position, thus admitting oil through the duct 14 at a maximum rate. As soon as the governor begins to move upwardly, due to an increase in the speed of the engine, the fuel inlet valve will be proportionately lowered, and the rate at which the fuel passes 80 through the duct 14 will be proportionately reduced.

The reservoir by which the charge of oil is maintained in relation to the engine cylinder is shown at 28 and is in the nature of a 85 cup, in which vaporization of the more volatile constituents of the oil takes place. In the instance disclosed, the valve 5 and the vaporizer cup 28 are connected to move as one element and the valve 5, together with a 90 cylindrical extension 29 thereof, forms a closure for the cup 28, which latter is preferably connected to the extension 29 by threads, as shown. The valve 5, at its base, is of less diameter than the extension 29, and 95 at the junction of said valve and said extension, an oil feed groove 30 is provided. The extension 29 works within the extension 3 of the plug 2 and the groove 30 is of less diameter at its highest edge than the inner 100 cylindrical wall of the extension 2, and consequently communicates with the interior of said extension 3 when the valve 5 is removed from its seat, as in Fig. 4. The groove 30 also communicates with the cup 28 by a 105 series of radially arranged passages 31.

The extension 3 of the plug 2 terminates at some distance above the lower end of the bore 1, and that portion of the bore 1 below said extension and in which the cup 28 is 110 arranged is in open communication with the combustion space of the engine cylinder and affords an annular chamber 32 in surrounding relation to the cup 28. As the clearance between the piston and the cylinder head is 115 relatively small and the ultimate compression space of the engine is correspondingly small, the temperature of the main body of the air charge becomes relatively high, but, on account of the relatively large wall surface from which heat will be derived by the air confined in the annular chamber 32, the temperature of the air at the upper part of this annular chamber becomes materially higher than the temperature of the main 120 body of the air charge. Thus, at a certain point near the end of the compression stroke, the temperature of the air confined in the chamber 32 becomes high enough to ignite the carbureted air in the cup 28 and in order

that the superheated air charge in the chamber 32 may serve this purpose, the cup 28 has at its upper end openings 33 of small diameter, by means of which the upper portion of the chamber 32 has restricted communication with the cup 28. The cup 28 is also provided with openings 34 which are located closely adjacent its bottom and through which the unvaporized fuel (which remains as a film on the bottom of said cup) is expelled into the combustion space of the engine cylinder consequent to the explosion which is set up in the cup 28 when the vaporized fuel in the latter is ignited 15 by the superheated air in the upper portion of the chamber 32. The preliminary explosion resulting from the ignition of the carbureted air confined in the reservoir 28 will effect a thorough heating, vaporizing, and 20 atomizing of the main fuel charge remaining in the reservoir 28 as said charge is forcibly ejected through the openings 34 to mix with the air contained in the combustion space. Immediately upon the preliminary 25 explosion there will, therefore, follow a gradual slower combustion of the fuel, until the last of it is consumed. The size and number of the openings 34 and their disposition with relation to the bottom of the 30 reservoir 28 will, to some extent, depend on the nature of the fuel utilized.

For oil burning engines of relatively large horsepower, a positive timing of the preliminary explosion by means of which the combustible fuel is expelled into the engine cylinder may be of advantage. When the embodiment herein disclosed is employed, this positive timing of the preliminary explosion is readily provided for by the use of 40 blocks 35, which are preferably arranged in air-tight relation in the chamber 32 and are of sufficient depth to control both the openings 33 and the openings 34. The blocks 35 thus act as valves and they may conveniently 45 be made as lugs which depend from the extension 3.

Fig. 3 shows the valve 5 and the oil cup 28 when the piston is about to start on its suction stroke, or is just completing its compression stroke. When the piston moves 50 downwardly on its suction stroke, the valve 5 and the cup 28 move as one from the position of Fig. 3 to the position of Fig. 4, wherein the valve 5 is distant from the seat 4 and the openings 34 are below the blocks 35. The suction developed by the piston induces the flow of oil and air through the passages 6 and 7 respectively, into the upper portion of the bore 1 and through the passages 31 which lead from the groove 30 into the cup 28, as indicated by the arrows. When the requisite amount of oil has been 55 passed to the cup 28, said cup and the valve 5 move upwardly as one from the position of 60 Fig. 4 back to the position of Fig. 3, wherein

the blocks 35 cover the openings 33 and 34 and thus shut off the communication between the openings 33 and the chamber 32, and the openings 34 and the combustion space. Thereafter, the piston ascends on its compression stroke, compressing the air previously admitted into the cylinder through the valve C and during compression, this air becomes heated, the air at the upper portion of the chamber 32 being considerably hotter than the remainder of the air charge, and attaining a sufficiently high temperature, to ignite those more volatile particles of oil in the cup 28, which have become vaporized consequent to the heat absorbed by said cup. When the piston has about completed its compression stroke, the valve 5 and the reservoir 28 are again operated, but in this latter instance, said valve and said reservoir are not given an axial 80 movement, but are merely turned sufficiently to bring the openings 33 and 34 out of line with the blocks 35 and to thus put said openings into communication with the chamber 32 and the combustion space respectively. 90 This operation, therefore, changes the reservoir 28 from the position of Fig. 6 to the position of Figs. 5, 7, and 9. Thereupon the preliminary explosion in the reservoir 3, by which the unvaporized oil in said reservoir is expelled into the engine cylinder, takes place in the manner already explained. When the unvaporized oil in the reservoir has been expelled therefrom, the valve 5 and the reservoir 28 are again turned previous 100 to the next suction stroke to the position of Fig. 6, and in such position, of course, have the relations shown in Fig. 3 and are ready for a repetition of the cycle of operations described. 105

The axial movements of the valve 5 and the reservoir 28 are effected by the lever F and by the spring 12, as above explained, the lever F producing a downward movement of said valve and said reservoir, and the spring 12 producing an upward movement thereof. Added connections are employed for effecting the turning movement of said valve and said reservoir, and these connections may conveniently comprise, a bell crank lever 36 which is pivotal coaxially with the levers F and is suitably operated from the cam shaft by a rod 37, a laterally projecting arm 38 on the stem 11, and a link 39 which connects the arm 38 and the depending arm of the lever 36 and is articulated with said arm 38 and lever 36 by ball joints. It will be observed that when the valve stem 11 is depressed by the lever F, to effect the opening of the valve 5, the lever 36 will remain stationary and consequently, owing to the operative connection between the stem 11 with the lever, there will be an incidental turning movement of the stem 11 and of the valve 5 and reservoir 28. This 115 120 125 130

incidental turning movement is, however, without effect, since the blocks 35 are of sufficient width to maintain the openings 33 closed throughout the axial movements of the reservoir 28. The said reservoir is objectively turned when the valve 5 has resumed the position shown in Fig. 3 and the lever F, which actuates said valve, is stationary, the connections 36, 37, 38, and 39 coming into action for this purpose and producing a sufficient turning movement of the reservoir 28 to bring the openings 33 and 34 thereof out of line with the blocks 35 and to thus provide for the ejection of the fuel into the combustion space.

While the construction herein described readily lends itself to the positive timing of the preliminary explosion in the reservoir 28, it may be used with equal advantage, in a number of instances, notably those wherein the engine is of relatively low horsepower, without any positive timing of the preliminary explosion. In such a case the blocks 35 are not employed, and the only movement which said reservoir has is an axial movement which, however, is not needed to establish its communication with the engine cylinder, but is of advantage in effecting the dislodgment of carbon from the outer surface of the reservoir 28 as soon as it deposits thereon, just as it is when the construction includes the blocks 35, in which case the axial movement of the reservoir is additionally effective to control the communication of said reservoir and the combustion space, as already explained. When the blocks 35 and the connections for turning the reservoir are not employed, so that the preliminary explosion in the reservoir is not positively timed, it is, nevertheless, a fact, providing the engine is of relatively small horsepower, that the times for the preliminary explosion occur in regular sequence during the operation of the engine, because the more volatile constituents in the reservoir 3, being relatively cold by reason of the fact that heat has been made latent during the process of vaporization, are not apt to ignite before the defined period of the stroke where the excessively heated air in the annular air chamber causes their ignition.

The construction herein described is of advantage for the reason that the reservoir 28 is continuously given a jogging action, so to speak, which prevents the deposit of carbon and, consequently, the choking of the apertures 33 and 34. The improved construction is also of advantage in that it may be manufactured at a very low cost. It will be observed that there are no special requirements as to the shape of the reservoir 28 and, consequently, it is possible to produce said reservoir from thin steel by a simple drawing operation. Furthermore, the area

of ground surfaces required is comparatively slight, and the outlines of said surfaces are simple. There is a distinct advantage in having the valve 5 and the reservoir 28 connected to move as one element, since the construction is thereby materially simplified and no parts are involved which are readily liable to breakage or undue wear.

It will be understood that no specific description herein contained is intended to put any limitation upon the scope of the appended claims which does not inhere in the language thereof.

Having fully described my invention, I claim:

1. The combination with a cylinder and a piston of an oil burning engine, of a cup which projects into the combustion space of the cylinder and to which a charge of fuel oil is supplied, the cup having openings through which the charge is expelled into the cylinder, and means for jogging the cup during the running of the engine.

2. The combination with a cylinder and a piston of an oil burning engine, of a cup which projects into the combustion space of the cylinder and to which a charge of fuel oil is supplied, the cup having openings through which the charge is expelled into the cylinder and having other openings for the purpose of igniting the vaporized constituents of the charge within the cup, the cylinder having a small chamber in open communication with the combustion space and in restricted communication, through said last named openings, with said cup and in which a portion of the main air charge becomes superheated during compression, and means for jogging the cup during the running of the engine.

3. The combination with a cylinder and a piston of an oil burning engine, the upper head of the cylinder having an internal valve seat and having oil and air passages which open to said seat, of a valve movable toward and away from said seat, an oil cup connected to said valve to move therewith and provided with fuel discharge openings, passages through which the oil flowing from said valve seat passes into said cup, and means for moving the valve toward and away from its seat at definite periods in the running of the engine.

4. The combination with a cylinder and a piston of an oil burning engine, a wall of the cylinder having passages for fuel oil and air, a movable valve to control the flow of oil and air from said passages, an oil cup connected to said valve to move therewith and provided with fuel discharge openings, other passages through which the oil passes into said cup in one position of the valve, and means for moving the valve toward and away from its seat at definite periods in the running of the engine.

5. The combination with a cylinder and a piston of an oil burning engine, the upper head of the cylinder having an internal valve seat and having oil and air passages which open to said seat, of a valve movable toward and away from said seat, an oil cup connected to said valve to move therewith and provided with fuel discharge openings, passage through which the oil flowing from 10 said valve seat passes into said cup, and means for moving the valve toward and away from its seat at definite periods in the running of the engine, the cylinder having a small chamber in open communication 15 with the combination space and in which a portion of the main air charge becomes superheated during compression and the oil cup having other openings of small diameter which afford communication between 20 said chamber and the interior of the oil cup and provide for an explosion of the vaporized oil in the cup consequent to the maximum heat developed in the chamber.
6. The combination with a cylinder and 25 a piston of an oil burning engine, a wall of the cylinder having passages for fuel oil and air, a movable valve to control the flow of oil and air from said passages, an oil cup connected to said valve to move therewith and provided with fuel discharge openings, other passages through which the oil passes into said cup in one position of the valve, and means for moving the valve toward and away from its seat at definite 30 periods in the running of the engine, the cylinder having a small chamber in open communication with the combustion space and in which a portion of the main air charge becomes superheated during compression 35 and the oil cup having other openings of small diameter which afford communication between said chamber and the interior of the oil cup and provide for an explosion of the vaporized oil in the cup consequent to the maximum heat developed in the chamber.
7. The combination with a cylinder and 40 a piston of an oil burning engine, the upper head of the cylinder having an internal valve seat and having oil and air passages which open to said seat, of a valve movable toward and away from said seat, a cylindrical oil cup threaded upon said valve to move therewith and provided with fuel discharge 45 openings, the valve having passages through which the oil flowing from said valve seat may pass into said cup when the valve is unseated, and means for moving the valve toward and away from its seat at definite periods in the running of the engine.
8. The combination with a cylinder and 50 a piston of an oil burning engine, of an oil reservoir having an area exposed to the combustion space of said cylinder and hav-
- ing restricted communication with said combustion space, a restricted chamber in open communication with said combustion space, the oil reservoir having small openings through which it may have restricted 70 communication with said chamber, a portion of the air admitted to the cylinder becoming heated in the chamber to a degree greater than that of the air remaining in the cylinder and sufficient to cause an explosion within the oil reservoir of the particles of oil in said reservoir which have become vaporized during compression, and means for positively establishing and disestablishing the communication of said chamber and reservoir through the small openings in the latter, at definite periods in the running of the engine.
9. The combination with a cylinder and 75 a piston of an oil burning engine, of an oil reservoir having an area exposed to the combustion space of said cylinder and having restricted communication with said combustion space, a restricted chamber in open communication with said combustion space and in restricted communication with the oil reservoir, a portion of the air admitted to the cylinder becoming heated in the chamber to a degree greater than that of the air remaining in the cylinder and sufficient to cause an explosion within the oil reservoir of the particles of oil in said reservoir which have become vaporized during compression, and means for shutting off the restricted 80 communication between said chamber and said reservoir except for a definite period in the running of the engine, and thereby positively timing the explosion.
10. The combination with a cylinder and 85 a piston of an oil burning engine, a wall of the cylinder having passages for fuel oil and air, a valve to control the flow of oil and air from said passages, the valve being both rotatably and axially movable, an oil cup connected to said valve to move therewith and provided with fuel discharge openings, other passages through which the oil passes into said cup in the open position 90 of the valve, the cylinder having a small chamber in open communication with the combustion space and in which a portion of the main air charge becomes superheated during compression and the oil cup having further openings of small diameter which afford communication between said chamber and the interior of the oil cup and promote an explosion of the vaporized oil in the cup consequent to the maximum heat developed 95 in the chamber, blocks arranged in the chamber to serve as closures for the openings of said oil cup, means for moving the valve toward and away from its seat at definite periods in the running of the engine, and means for turning the valve upon its seat at other definite periods in the running of 100 the engine.
11. The combination with a cylinder and 105 a piston of an oil burning engine, a wall of the cylinder having passages for fuel oil and air, a valve to control the flow of oil and air from said passages, the valve being both rotatably and axially movable, an oil cup connected to said valve to move therewith and provided with fuel discharge openings, other passages through which the oil passes into said cup in the open position 110 of the valve, the cylinder having a small chamber in open communication with the combustion space and in which a portion of the main air charge becomes superheated during compression and the oil cup having further openings of small diameter which afford communication between said chamber and the interior of the oil cup and promote an explosion of the vaporized oil in the cup consequent to the maximum heat developed 115 in the chamber, blocks arranged in the chamber to serve as closures for the openings of said oil cup, means for moving the valve toward and away from its seat at definite periods in the running of the engine, and means for turning the valve upon its seat at other definite periods in the running of the engine.
12. The combination with a cylinder and 120 a piston of an oil burning engine, a wall of the cylinder having passages for fuel oil and air, a valve to control the flow of oil and air from said passages, the valve being both rotatably and axially movable, an oil cup connected to said valve to move therewith and provided with fuel discharge openings, other passages through which the oil passes into said cup in the open position 125 of the valve, the cylinder having a small chamber in open communication with the combustion space and in which a portion of the main air charge becomes superheated during compression and the oil cup having further openings of small diameter which afford communication between said chamber and the interior of the oil cup and promote an explosion of the vaporized oil in the cup consequent to the maximum heat developed in the chamber, blocks arranged in the chamber to serve as closures for the openings of said oil cup, means for moving the valve toward and away from its seat at definite periods in the running of the engine, and means for turning the valve upon its seat at other definite periods in the running of the engine.

- the engine, to thereby establish communication between the openings in the oil cup and the small chamber and the combustion space of the engine, respectively.
- 5 11. The combination with a cylinder and a piston of an oil burning engine, a wall of the cylinder having passages for fuel oil and air, an axially movable valve to control the flow of oil and air from said passages, an oil cup connected to said valve to move therewith and provided with fuel discharge openings, other passages through which the oil passes into said cup in the open position of said valve, the cylinder 10 having a small chamber in open communication with the combustion space and in which a portion of the main air charge becomes superheated during compression and the oil cup having other openings of small diameter 15 which afford communication between said chamber and the interior of the oil cup and promote an explosion of the vaporized oil in the cup consequent to the maximum heat developed in the chamber, means for moving 20 the valve toward and away from its seat at definite periods in the running of the engine, 25

blocks arranged in the chamber to control the openings in the oil cup, and means for producing a relative rotative movement between the oil cup and the blocks 30 whereby to establish communication between the openings in the oil cup and the chamber and combustion space of the cylinder, respectively.

12. The combination with a cylinder and a piston of an oil burning engine, of an oil cup subject to the heat developed in the combustion space and communicating therewith through small ports, closers for said ports, and means for effecting relative movements 35 of the oil cup and the port closers in timed relation to the strokes of the piston to positively establish or disestablish the communication of said cup and said combustion space through said ports.

45 In testimony whereof I have hereunto set my hand in presence of two subscribing witnesses.
